(57) **CLAIM**

The ornamental design for a cabinet panel, as shown and described.

DESCRIPTION

FIG. 1 is a perspective view of the cabinet panel.

FIG. 2 is a front elevational view of the cabinet panel; and, FIG. 3 is a perspective view of a cabinet having the cabinet panel incorporated therein.

The back, top, bottom and side edges form no part of the claimed design.

Portions of the drawings shown in broken lines form no part of the claimed design.
